CLAIM

We claim the ornamental design for housing portions of a cam lock, as shown and described.

DESCRIPTION

FIG. 1 is a perspective view showing a first form of our new design;

FIG. 2 is a front elevational view thereof;

FIG. 3 is a right side elevational view thereof, the left side being a mirror image of that shown;

FIG. 4 is a top plan view thereof, the bottom being a mirror image of that shown;

FIG. 5 is a perspective view showing a second form of our new design, it being understood that a right elevational view thereof would be identical to the image of FIG. 3, that the left side would be a mirror image of FIG. 3, and that a top plan view thereof would be identical to FIG. 4; and, FIG. 6 is a front elevational view thereof.

The broken-line disclosure of elements of a cam latch is provided for illustrative purposes only and forms no part of the claimed first, second and third design forms.
